UNITED STATES PATENT OFFICE.

HANS P. PETERSEN, OF SOUTH TACOMA, WASHINGTON.

DESIGN FOR A WRENCH.

47,435.

Specification for Design.

Patented June 8, 1915.

Application filed August 29, 1914. Serial No. 859,250. Term of patent 14 years.

To all whom it may concern:

Be it known that I, HANS P. PETERSEN, a subject of the King of Denmark, residing at South Tacoma, in the county of Pierce and State of Washington, have invented a new, original, and ornamental Design for a Wrench, of which the following is a specification, reference being had to the accompanying drawing, forming a part thereof.

Figure 1 is a side elevation of a wrench

showing my design; and Fig. 2 is a top plan view of the same.

I claim:

The ornamental design for a wrench as shown.

HANS P. PETERSEN.
